PIERRE AUGUSTIN SAMUEL, OF PARIS, FRANCE.

Letters Patent No. 86,181, dated January 26, 1869.

IMPROVEMENT IN WRENCH.

The Schedule referred to in these Letters Patent and making part of the same.

To all whom it may concern:

Be it known that I, PIERRE AUGUSTIN SAMUEL, of Paris, in the French Empire, civil engineer, have invented "a new System of Extensible Wrench, so-called 'Universal Key,' for tightening pipes and other cylindrical and other bodies;" and I do hereby declare that the following is a full, clear, and exact description of the same, reference being had to the annexed sheet of drawings, making a part of the same.

My invention consists in a new system of extensible key or wrench, for the especial purpose of tightening pipes and cylindrical bodies, but also applicable to tightening bolts and other bodies of polygonal form.

The extensible key, which forms the object of the present application for Letters Patent of the United States, has, for characteristic feature, a double cam, fixedly secured within the key-terminating caps, and acting on the ends of swivel-levers, for the purpose of operating a lockage, which is automatic, and the more energetic as the traction on the key-handle is stronger.

I have just said that the double cam, actuating the two ends of the swivel-levers, is an independent piece, fixed steadily and rigidly within the cap which terminates one of the key-ends, but it will be understood that the same double cam may be cast with the key-handle, and the construction of the tool be simplified thereby.

This new system of extensible key, by its working self-actingly, energetically, and without any slipping of the cylindrical surface, permits and popularizes, as it were, the use, restricted heretofore, of screw-nuts of cylindrical form, with or without striae or corrugations on their external periphery, which, till now, could not be of any practical use, as there existed not any tool for the tightening and loosening thereof.

Another advantage of my new extensible key is, that as it is acting ratchet-like, or on very small portions of surfaces, it can work within very limited spaces, in corners, for instance, and wherever the course of the tool is limited.

I have, in the accompanying drawings, represented two arrangements of my new system of extensible key

intended for tightening and loosening pipes, nut-screws, and other cylindrical or other bodies.

Figure 1 is a front external view of a first arrangement of the said key or wrench.

Figure 2 is a central longitudinal section of the same, showing an edge view of the tool.

Figure 3 shows, in detail, one of the flanges, to which are jointed the extensible swivel-jaws.

Figure 4 shows, on a larger scale, and in section, the key-head, and the way in which the swivel-jaws are acted upon by the cams.

Figure 5 is a front view of another arrangement of the same key, in which the double cam, instead of being an independent piece, is cast with the handle of the tool.

In all these figures the same letters of reference indicate the same parts where they recur.

a, tool-lever or handle, terminated at one end by a knob, and at the other by a cap, *b*.

c, double cam, secured rigid and motionless to the cap by two rivets *d*.

This double cam has on each side a bracket, on which are turning the two flanges *f*, shown in detail, fig. 3.

g, swivel-jaws or clamps jointed at *h* to the flanges *f*. These clamps, which are toothed internally and inversely to tightening are extensible, and actuated by the double cam *c*.

I must observe, in this place, that the double cam is terminated on each side, at its lower part, by a notch, to admit the ends of the swivel-levers at their furthest position, for the purpose of liberating the key readily from the cylinder acted upon.

Claim.

The new extensible key or wrench, for tightening and loosening pipes, screw-nuts, and other bodies of circular and other sections, which is chiefly characterized by its extensible swivel-clamps or jaws, acted upon by a double-bent cam or eccentric, as described, and represented in the accompanying drawings.

Witnesses:
